UNITED STATES PATENT OFFICE

120,988

DESIGN FOR A FISH BAIT

**Kenneth Curtis, Winnetka, Ill., assignor to Eger
Bait Manufacturing Company, Bartow, Fla.,
a corporation of Florida**

Application September 16, 1939, Serial No. 87,255

Term of patent 7 years

To all whom it may concern:

Be it known that I, Kenneth Curtis, a citizen of the United States, residing at Winnetka, county of Cook, and State of Illinois, have invented a new, original, and ornamental Design for a Fish Bait, of which the following is a specification, reference being had to the accompanying drawing, forming a part thereof, in which:

Figure 1 is a side elevational view of a fish bait, showing my new design; and Fig. 2, a plan view of the same.

I claim:

The ornamental design for a fish bait, as shown.

KENNETH CURTIS.
